UNITED STATES PATENT OFFICE.

FRED AUGUST WOLF, OF QUINCY, ILLINOIS.

DESIGN FOR A PHONOGRAPH CABINET.

Application filed May 31, 1923. Serial No. 6,357. Term of patent 3½ years.

To all whom it may concern:

Be it known that I, FRED AUGUST WOLF, a citizen of the United States, residing at Quincy, in the county of Adams and State of Illinois, have invented a new, original, and ornamental Design for Phonograph Cabinets, of which the following is a specification, reference being had to the accompanying drawing, forming part thereof.

The figure is a perspective view of a phonograph cabinet, showing my new design.

I claim:—

The ornamental design for a phonograph cabinet, as shown.

FRED AUGUST WOLF.
